HINGE FOR OFFSET DOORS

Frank P. Agius, 1027 Meyers Road, Alpena, Mich.
Filed Mar. 1, 1961, Ser. No. 92,610

2 Claims. (Cl. 16—135)

My invention relates generally to door hinges, and more particularly to hinges for cabinet doors.

The improved hinge of my invention can be used readily with inset or lipped cabinet doors. It is capable of accommodating 180 degrees of swing, and when the door is closed it is concealed substantially when the door is viewed from the front of the cabinet.

My improved hinge construction makes it possible for a cabinet maker to eliminate unsightly pin or bolt hinges of conventional construction. The door can be finished to provide an overall clean appearance since the hinge elements are concealed substantially by the lipped portions of the door. Lipped doors can therefore be used in special applications where they could not have been used before.

For the purpose of particularly describing a preferred embodiment of my invention, reference will be made to the accompanying drawing wherein:

FIG. 1 shows a front elevation view of a cabinet door employing the hinge construction of my invention;

FIG. 2 is an enlarged front elevation view of a portion of the cabinet door shown in FIG. 1;

FIG. 3 is a partial cross sectional view of the door of FIGS. 1 and 2 and is taken along section line 3—3 of FIG. 2;

FIG. 4 is a partial cross sectional view of the door of FIGS. 1 and 2 and is taken along section line 4—4 of FIG. 2;

FIG. 5 is a view similar to the view of FIG. 3 but showing the cabinet door in a full open position;

FIG. 6 is a front elevation view of the cabinet when the door assumes the position shown in FIG. 5; and

FIG. 7 is an isometric view of the offset hinge illustrated in the other views.

Referring first to FIG. 1, numeral 10 designates a cabinet door and numeral 12 designates a door frame. The door 10 is hinged at the top and bottom so that it will pivot about the left hand margin of the door as viewed in FIG. 1. Numeral 14 designates a knob or handle for opening and closing the door.

The hinge on the upper portion of the door 10 is shown in FIG. 2 and is generally designated by reference character 16. It will be apparent from an inspection of the views that the hinge 16 conforms to the configuration of the periphery of the door 10.

As previously indicated, the door 10 is formed with a recessed or lipped periphery, the lipped portion being designated by reference character 18. The portion of the door covering the opening of the frame 12 is inset within the door opening and is designated by reference character 20. The lipped portion 18 is adapted to overlie the periphery of the frame 12.

The hinge 16 comprises two portions that are separately identified by reference characters 22 and 24. The portion 22 is adapted to be secured to the frame 12 and the portion 24 is adapted to be secured to the door 10.

The portion 22 includes a base plate 26 that is adapted to be bolted to the inner peripheral surface 28 of the frame 12, suitable screws 30 being provided for this purpose. An upright portion 32 is disposed at right angles with respect to the plane of portion 26 and it is flush with respect to the outer surface 34 of the door frame 12.

Hinge portion 22 further includes an offset tab 36 formed at right angles to the portion 32 in a plane parallel to the portion 26. The tab 36 is relatively small and is formed with a pin opening for accommodating a

2

pin rivet 38. This pin 38 forms the sole connection between hinge portions 22 and 24.

As indicated in the views, tab 36 is adapted to overlie the outer periphery of the door 10.

Hinge portion 24 includes a base 40 that can be screwed to the inner surface of the inset portion 20 of the door 10 as shown in FIG. 6. Hinge portion 24 is deformed to form a right angle portion 42 that is situated in engagement with and in face-to-face relationship to the upper surface of the inset portion 20 of the door 10.

Another portion 44 is formed at right angles with respect to the plane of portion 42 and this portion 44 is situated in engagement with and in face-to-face relationship to the inner surface of the lipped portion 18 of the door 10. Hinge portion 24 further includes an offset tab 46 situated at right angles with respect to the portion 44. Tab 46 overlies the upper edge of the lipped portion 18 of the door 10. The plane of the tab 46 is parallel to the plane of the portion 42. The tab 46 is pinned as shown to the tab 36 by the aforementioned pin 38.

The base 40 of the hinge portion 24 is formed with three screw holes separately identified by reference characters 48, 50 and 52.

In assembling the door, screws 54 and 56 are used for initially securing a door 10 within the opening of frame 12. The screw openings 48 and 50 are elongated as indicated to permit a degree of adjustment of the door with respect to the frame when it is assembled in place. If the proper adjustment has been obtained, the screws 54 and 56 are tightened and a third screw 58 is inserted in the screw opening 52 to lock the hinge portion 24 securely in place with respect to the door 10.

The pin 38 is located relatively close to the plane of upright portion 32 of the hinge portion 22. The spacing is sufficient, however, to avoid interference between the lipped door portion 18 and the frame 12 when the door is opened, as indicated in FIG. 5.

When the door 10 is in the closed position, the hinge 16 is concealed substantially. The only portion of the hinge that is visible to the observer is the edge of the tabs 36 and 46.

The hinge portions can be formed during manufacture by a suitable stamping operation.

As best observed in FIG. 4, the opening in tab 46 for the pin 38 offset to permit clearance between the frame 12 and the inner edge of the lipped portion 18 of the door 10. This clearance is equal to the combined thickness of the hinge portions 32 and 44.

The hinge at the lower margin of the door 10 will, of course, be a mirror image of the hinge 16 illustrated in the drawings. These hinges can be manufactured in pairs.

Having thus described a preferred embodiment of my invention, what I claim and desire to secure by U.S. Letters Patent is:

1. A hinge for mounting a rectangular lipped door within a frame having upper and lower horizontal portions and vertical side portions, the door being inset with respect to the frame and the peripheral portion of the door overlying the outer surface of the frame, said hinge comprising a frame plate and a door plate, said frame plate being adapted to be secured to the inner periphery of one of said horizontal frame portions and including a side portion situated in face-to-face relationship with respect to the outer surface of said frame, a tab formed on and disposed at right angles with respect to said side portion, said door plate comprising a portion secured to the inner inset portion of said door, a portion situated at right angles with respect to said first named portion and an upright portion situated in face-to-face relationship with respect to the inner surface of the lipped periphery of said door, a tab on said door plate situated in mating relationship with respect to the tab on said frame plate, said

door plate tab extending in a plane perpendicular to said upright portion, and means for pinning said tabs together.

2. A hinge for mounting a rectangular lipped door within a frame having upper and lower horizontal portions and vertical side portions, the door being inset with respect to the frame and the peripheral portion of said door overlying the outer surface of said frame, said hinge comprising a frame plate, said frame plate including a first portion adapted to be secured to the inner peripheral surface of said frame, a second portion adapted to overlie the outer surface of said frame in face-to-face relationship with respect to the same, and a third portion extending in a plane perpendicular to said second portion, said hinge including also a door plate, said door plate having a first portion, means for securing said first portion to the inner inset surface of said door comprising spaced screw holes therein, at least one of said screw holes being elongated, and screws extending through said holes into said inset surface whereby an adjustment of said door within said frame assembly can be obtained before the door is permanently secured to said door plate, a second portion disposed at right angles with respect to said first portion and adapted to overlie the peripheral surface of

10

15

20

said inert portion, a third portion situated perpendicular with respect to said second portion, and a fourth portion extending perpendicularly with respect to said first and third portions, the fourth portion of said door plate being pinned to the third portion of said frame plate, the first, second, and third portions of said plate being concealed entirely when said door is closed and the door is viewed along a line of vision that is perpendicular to the plane of the door.
